CLAIM

The ornamental design for a cushion for use by a child in conjunction with an adult vehicle safety belt, as shown and described.

DESCRIPTION

FIG. 1 is a front perspective view of a cushion for use by a child in conjunction with an adult vehicle safety belt showing my new design.

FIG. 2 is a perspective view from in front, below and one side.

FIG. 3 is a view from one side (the view from the other side corresponds).

FIG. 4 is a front view.

FIG. 5 is a rear view.
